United States Patent Office.

HUBERT BURGESS, OF SAN FRANCISCO, CALIFORNIA.

Letters Patent No. 95,766, dated October 12, 1869.

IMPROVEMENT IN PAPER-FILES.

The Schedule referred to in these Letters Patent and making part of the same.

To all whom it may concern:

Be it known that I, HUBERT BURGESS, of San Francisco, in the county of San Francisco, and State of California, have invented a new and useful Improvement in Paper-Files; and I do hereby declare that the following is a full, clear, and exact description thereof, which will enable others skilled in the art to make and use the same, reference being had to the accompanying drawing, forming part of this specification.

This invention relates to improvements in files for papers, music in sheets, &c., and the combination therewith of a portfolio, whereby it is designed to provide a simple and convenient arrangement of clamping-jaws for holding the paper, permitting the engagement with or disengagement from it, of the papers, with facility, the said jaws being actuated by screws and springs, and capable of employment either with or without the portfolio.

In the accompanying drawings—

Figure 1 represents a transverse section of my improved file and portfolio, the latter being in a closed position.

Figure 2 represents a plan view of the same in an open position.

Similar letters of reference indicate like parts.

A represents one of the clamping-jaws, provided with angular metallic pieces, B, the parts B' of which are rigidly secured to the outer face of the jaw, the other parts being turned at right angles thereto, under the bottom thereof, forming a means, in combination with other similarly-formed angle-pieces, C, made fast to the other jaw, D, upon the outside, of maintaining the jaws in the right position to clamp the papers to be held in the file at the outer edges of the jaw.

E represents bolts, having nuts for forcing the jaws together, to clamp the paper, which are preferably arranged to pass through the said metallic angle-pieces B and C, and made fast in the jaws A. As it is desirable, in order to give ample room for inserting the papers within the jaws, that the bolts pass through the said jaws below the centre line, or nearer to the back than the front of the same, the tendency of the jaws, when screwed up, would be to close nearer together at the back than at the front without the arrangement of the angle-pieces B and C, as above described.

F represents springs, arranged between the jaws, to cause them to open when the nuts of the bolts E are turned in the right direction. These springs are placed at the rear or bottom of the clamping-jaws,

and below the line of the bolts, whereby they assist the angle-pieces in causing the jaws to bite at their outer edges.

The angle-pieces B are provided with screw-holes, to admit of fastening them, by screws, H, to the inner side of the back of a portfolio, I, as represented at G, or they may be permanently attached thereto by rivets, or other means.

By this arrangement, it will be seen that my improved file is equally well adapted for use separately, or combined with a portfolio.

When it is used in combination with a portfolio, as a music-file, it is desirable to insure the opening and adjustment of the two parts of the portfolio in the same plane, in order that the bottom edges will rest properly on the narrow shelves of the music-stands. To insure this, I arrange recesses in the bottom edges of the jaws, for the insertion of the shank of the wrench K, which is also used for turning the nuts of the bolts E, between the jaws and the portfolio, as represented in red in fig. 2, whereby they will be secured in the right position to be supported in the best manner on the said music-stand, as will be clearly understood.

Instead, however, of making recesses in the jaws, as described, the portfolio may be sprung away from them sufficiently to admit of the insertion of the wrench, or any similar thing.

Having thus described my invention, I claim as new, and desire to secure by Letters Patent—

1. A pair of clamping-bars or jaws, A and D, held parallel or nearly parallel, by their flanges or angle-pieces B and C, and by the bolts E, that draw them together, and so arranged as to clamp and hold the edges of papers, music-sheets, &c., without perforating them, substantially as described.

2. In combination with the clamping-bars, constructed as described, a portfolio, provided with a rigid back, G, to serve as a means of connecting the clamping-bars of the file to the portfolio, substantially as described.

3. In combination with the clamping-bars of a paper-file and portfolio, the bar K, fitted to notches in the clamping-bars to hold the portfolio open and spread the music-sheets, &c., whether applied as a wrench or otherwise, substantially as set forth.

HUBERT BURGESS.
